Des. 234,639
Patented Mar. 25, 1975

234,639

HEMODIALYSIS MACHINE

Clarence Edwin Schmidt, 2741 E. Palmyra,
Orange, Calif. 92669

Filed Dec. 6, 1972, Ser. No. 312,762

Term of patent 14 years

Int. Cl. D24—01

U.S. Cl. D83—1 F

FIG.1

FIG.2

FIG.3

FIG.4

FIG.5

FIG.6

FIG. 1 is a front perspective view of a hemodialysis machine showing my new design;

FIG. 2 is a front elevation thereof;

FIG. 3 is a rear elevation thereof;

FIG. 4 is a top plan view thereof;

FIG. 5 is a bottom plan view thereof; and

FIG. 6 is an end elevation thereof.

I claim:

The ornamental design for a hemodialysis machine, substantially as shown and described.
